METAL WINDOW SASH

Harry H. Goldberg, Denver, Colo.

Application December 23, 1946, Serial No. 717,892

2 Claims. (Cl. 287—51)

1

This invention relates to improvements in metal window sash and has reference more particularly to the manner of effecting joints between the several frame members of which the sash is composed.

Metal window sash are made from steel or aluminum or any other suitable metal, the most popular metal today being aluminum because this can be extruded, thereby making it possible to get cross sections that would be difficult to obtain in any other way.

The several members of which the sash is formed are nearly always connected by welding, which is very satisfactory for most joints, but in certain places welded connections of the kind that have usually been provided have some objectionable features and it is the object of this invention to produce a construction in which the several parts may be interconnected in a manner that obviates some of the objections that can be made to a welded joint and which, also, may be effected in a simpler and cheaper manner.

This invention can be most readily understood when reference is had to the accompanying drawing in which it has been illustrated, and in which:

Figure 1 is a diagrammatic side elevation of a metal window sash showing the same divided into seven sections;

Figure 2 is a section to an enlarged scale, taken on line 2—2, Figure 1;

Figure 3 is a section on the same scale as that shown in Figure 2, taken on line 3—3, Figure 2;

Figure 4 is a view in the nature of a perspective showing the method of interconnecting two of the sash frame members;

Figure 5 is a cross section of frame member D.

In the drawing, in Figure 1, one specific type of window sash has been illustrated in a general way. The outer frame members have been designated by "A" and have a cross section like that shown in Figures 2, 3 and 4. The vertical side members are interconnected by a transom bar E that is positioned nearer the top than the bottom so as to form two openings of unequal size. The upper opening has been divided into four sections by bars D and the lower opening into three sections by bars C. The center opening, which has been designated by F, is for the reception of a hinged sash that has not been shown in the drawing. The other openings are usually filled by glass panes.

Referring now to Figure 2, it will be observed that the outer frame member A comprises a rectangular tubular center portion having an outwardly extending flange 10, and parallel

2

therewith is a flange 11 that is narrower than flange 10. Flanges 10 and 11 cooperate to secure the sash to an opening in a brick wall or in any other wall to which the sash is connected. Extending inwardly from the rectangular web of member A is a flange that has been designated by reference numeral 12 and serves as the abutment for a window pane. A small portion of the window pane has been shown in Figure 2 and designated by reference numeral 13. This is held in place by the usual putty seal 14. Transom bar E has a transverse web 15 having oppositely extending flanges 16 that serve as abutments for the window pane. Extending upwardly a short distance on the outside of member E is a wall or flange 17 that terminates in an outwardly extending and downwardly flaring ledge 18. At several spaced points, the opening above the transom bar is divided into sections by short pieces of specially constructed frame members D, which has been shown in section in Figure 5. It will be observed that these frame members D comprise a central rectangular portion formed from two web walls 19 that are spaced apart a short distance. Along one edge of the tubular web are two flanges 20 that extend equal distances from the center portion and along the other edge are flanges 21 that extend shorter distances. The lower opening is divided into three sections by frame members C whose construction is quite clearly shown in Figures 3 and 4. These members have a rectangular central web formed by walls 22 that are spaced apart a distance equal to the distance between the outer surfaces of webs 19 of frame members D. Flanges 23 extend equal distances from both sides of web 22, as shown most clearly in Figure 4 and narrower flanges 24 extend from the web 22 along its outer edge. Connection is made between frame members A and C in the manner shown in Figure 4 from which it will be seen that the inner web 25 of member A has a rectangular opening through which web 22 extends. The ends of web walls 22 are bent outwardly so as to form interlocks like those designated by reference numeral 31. In order to make it possible to rivet the ends of flanges 22 in the manner shown in the drawing, web 28 of frame members A is provided with a hole 29, through which the riveting tool may be introduced. If desired, the interlocks 31 may be secured to web 25 by welding in addition to the interconnection shown. Transom bar E has its web 15 provided with rectangular openings of a size to receive the spaced walls 22 of frame members C whose ends are then bent outwardly or

riveted as indicated at 30. Members D are secured in position between the upper frame member A and the transom bar in the manner shown in Figure 3. It will be seen that the web walls 19 project between the upper ends of web walls 22 of frame member C. The spreading or riveting of the web walls 19 is effected by a tool extending through the opening 29, which is provided especially for this purpose.

Referring now particularly to the joint between members C, D and E shown in Figure 3, it will be observed that web walls 22 extend through an opening in web 15 and receive between them web walls 19. A small amount of welding can be employed to interconnect the parts if desired.

With the ordinary construction in which the parts are butt welded to the outer frame, it often becomes necessary to employ a chisel to cut away some of the material that results from the welding operation, and besides this, it is more difficult and requires more time and effort to interconnect the members in the ordinary way than with the construction shown on the accompanying drawing.

Attention in particular is called to the joint shown in Figure 3 between parts C, D and E and also to the construction of the outer frame member A. All of these different structural forms cooperate in producing a sash of a simple and highly efficient construction that is free from many of the objectional features that result from the usual butt welding operation.

Having described the invention what is claimed as new is:

1. A window sash frame member for use in making metal window sash, comprising, a substantially rectangular tubular web, one side having a window pane abutment flange along one edge and a putty abutment flange along the other

edge, the web wall between the flanges having a rectangular opening for the reception of a web of another frame member, the opposite web wall having an opening in register with the first opening for the introduction of a riveting tool.

2. In a window sash comprising two frame members each of which has two parallel flanges spaced apart and interconnected by a tubular web of rectangular cross section, in which one frame member is connected with the other in substantially right angular relation, forming a T, the frame member forming the top of the T having one web wall provided with a transverse opening adapted to receive the web of the member forming the stem, the flanges of the latter being cut back to permit the web to project through the opening in the web of the top member, the other web wall of the top member having an opening in alignment with the opening in the other wall, for the reception of a riveting tool, whereby the ends of the web walls of the stem member may be spread apart, into web overlapping position, the outward flared ends forming means for holding the frame members in assembled position.
